3,000,096 CAN OPENERS

Daniel T. Cushler, Los Angeles, Calif., and Edwin A. McKesson, 422 Oakhurst, Los Angeles, Calif.; said Daniel T. Cushler assignor to Ethel Williamson, Detroit, Mich.

Substituted for abandoned application Ser. No. 330,654, Jan. 12, 1953. This application June 29, 1959, Ser. No. 826,387

3 Claims. (Cl. 30—10)

This invention relates to can openers, and more particularly to that lever type of can opener which may be anchored to the can to be opened, its lever being then rocked so that an end portion thereof is forced through the top of the can to cut or punch a hole through which the contents of the can may be dispensed.

The main objects of the invention are to provide a can opener of the character indicated which may be conveniently applied and used on cans of a type which lack pronounced beads around their ends by which conventional can openers of the character indicated are pivotally anchored in place on the can to facilitate can opening movement of the lever as aforesaid; to provide such a can opener which will be operative to produce dispensing openings of substantially uniform size and shape in successive cans, thereby to facilitate the application of a pouring spout of predetermined size and shape to a succession of cans; to provide a rigid and durable can opener of the character indicated and one embodying relatively simple parts which may be manufactured at low cost and quickly and easily assembled; and other objects and advantages of the invention will be understood by reference to the following specification and accompanying drawing disclosing a can opener embodying a selected form of the invention.

In the drawing,

FIG. 1 is a side elevation in partial section, showing our improved can opener in use;

FIG. 2 is a top view of a can illustrating the form of dispensing opening produced by the can opener;

FIG. 3 is a perspective illustration of a type of pouring spout which may be inserted and seated in the dispensing opening formed by the can opener herein described;

FIGS. 4 and 5 are perspective illustrations of the component parts of the can opener;

FIG. 6 is a cross section on the plane indicated by the line 6—6 of FIG. 1, and

FIG. 7 is a cross section on the plane indicated by the line 7—7 of FIG. 4.

The can 1 shown in the drawing is typified by metal cans which are presently commonly used for the packing of condensed milk and perhaps other products. Its top and bottom end members 2 and 3 respectively, are secured to the marginal end portions of the can shown by means of flanges such as indicated at 4, which extend from the periphery of the ends 2 and 3 into overlapping relation to the margins of the body of the can. These flanges 4 are usually of only the thickness of the metal of which the can ends are made, and they provide shoulders such as indicated at 5, which are too small to permit anchoring of conventional can openers on the can end.

The can opener shown by the drawing comprises a can side engaging elongated support 6 which has a fixed ledge 7 extending laterally from its lower end. Such support is formed with similar upper and lower pairs of edgewise extending ears 8 and 9 respectively, which are preferably bent slightly out of the plane of the body portion of the support so as to produce a more or less arcuate transverse shape in the areas of said ears to more or less fit the curvature of a can body and to provide a

2

somewhat wider area of engagement with the side of the can than is afforded by the main body portion of the support. To strengthen said support, it is formed with a centrally disposed elongated rib 10 pressed outwardly from the support along most of the length thereof as shown. The upper end of the support is integrally formed with a pair of opposed edgewise-extending trunnions 11—11. The described support may readily be stamped and formed from sheet metal of desired thickness.

The other major component of the can opener is a lever member 12 which embodies a handle member 13 and a can puncturing blade 14, the latter being of more or less triangular shape and pointed to the free end of the lever. The blade 14 is bent to an angle of about 45° relative to the length of the handle member. Adjacent the junction of the blade 14 and handle member there is provided a pair of aligned bearings 15—15 on opposite edges of the lever, these bearings being adapted to receiving the trunnions 11 so as to pivotally mount the lever on the support.

The bearings 15 are formed from strips of metal partially cut out of the handle member and rolled to tubular form, as shown, leaving recesses 16—16 in the opposite edges of the handle member adjacent the juncture of said blade and member. As shown, the bearings ears 15 are formed to project from the plane of the handle 13 in the same direction that the blade 14 is bent to its aforesaid angular position. For assembly purposes, the bearings 15—15 are each initially formed into a U shape so that they may be hooked over the trunnions 11, after which they are subjected to further rolling or bending to close the same into more or less completely circular form shown in FIG. 1. The lever 12 is also reinforced 35 by means of an outwardly pressed rib 17 approximately coextensive with the handle 13.

The described can opener is used by seating a can to be opened upon the ledge 7 and adjusting such can into engagement with the support 6 or the ears 8 and 9 thereof, as shown in FIG. 1. The lever is initially in a position such as illustrated by broken lines in FIG. 1. The lever is then rocked about its fulcrum established by the trunnions 11 to move the blade 14 downwardly into engagement with the can top, whereupon further rocking of the lever to the position shown in full lines in FIG. 1 will cause said blade to cut out of the can top and bend downwardly into the can a triangular ear 18, the latter remaining integrally connected to the top along a line 19 on which said ear 18 is bent.

A stop pin 20 is secured to the upper end portion of the support so that it will overlie the can top although not necessarily in engagement with the latter. Said stop pin is preferably located in the support closely adjacent to the can top. Said stop pin is engageable by the blade 14 when the lever 12 has been rocked sufficiently to form an opening 21 of predetermined size. It will be seen that cans of the same depth will be so engaged by the opener that their tops will always occupy substantially the same relationship to the fulcrum of the lever. Hence, the openings 21 formed in like cans will be of substantially like size and shape.

Certain products packaged in cans of the type illustrated, are distributed in two standardized sizes of cans, the larger of which is represented in FIG. 1. For accommodating the described can opener to cans of the smaller standard size (not shown), the support 6 is provided with an auxiliary ledge pin 22 received in an opening 23 of the support and slidably in such opening to project selectively to either side of the support. As shown in FIGS. 1 and 6, the auxiliary ledge pin 22 is in its outwardly projected position of non-use, and said pin is provided with headed ends 24a and 24b which limit

sliding of the pin and prevent its escape from the support. When a smaller sized can is to be opened, the auxiliary ledge pin 22 is shifted to an inwardly projecting position (not shown) in which it overlies the ledge 7 and serves the purpose of such ledge except that it is adapted to support smaller sized cans of a height corresponding approximately to the distance between the upper side of the ledge pin 22 and the stop pin 20. Hence, it will be seen that by seating the smaller sized or shorter cans on the pin 22, their tops will have the same relationship to the axis of the trunnions 11 as the tops of the larger sized cans supported on the lower end ledge 7 as illustrated in FIG. 1, and that when the lever 12 is rocked until its puncturing blade engages the stop pin 20, the same sized opening may be produced in both sizes of cans.

With the described means for producing uniform dispensing openings in both standard sizes of cans, it is convenient to employ a pouring spout 25 of the character indicated in FIG. 3 for use with such cans. Said spout comprises a triangular base portion 26 of compressible plastic or rubber material of a size to fit frictionally in the opening 21, the friction fit being such that the spout will be effectively held in place on the can. The production of substantially uniformly sized and shaped openings in the can tops is thus highly advantageous in connection with the use of a pouring spout of the character indicated.

The stop pin 20 is shown in FIG. 7 as having the form of a shouldered rivet anchored in place by a headed end portion. This rivet form of stop pin is preferred in that it facilitates the provision of any desired length of such pin. The latter may, of course, be replaced by an ear punched and bent out of the support 6, but this is considered somewhat less desirable for the reason that such a punched and bent ear necessitates a relatively large opening or slot in the support which will weaken the latter adjacent the trunnions 11 where relatively great strength is desirable. However, in some instances a punched and inwardly bent stop pin may be satisfactorily employed.

Various other changes may be made in the described construction while retaining the principles of the invention.

What we claim is:

1. An opener for a can having upper and lower ends, 45

said opener including a lever and a cutting blade formed by an end portion of such lever, a handle member rigidly extending from said blade, an elongated support for said lever exteriorly engageable with a can wall and proportioned to extend approximately from end to end of an engaged can, means for fulcruming the lever on the upper end of said support substantially at the juncture of said blade and handle member, such means establishing a substantially horizontal axis, about which the blade may be forced downwardly to puncture the upper end of said can, a stop member fixed on said support below and adjacent to the fulcrum means and projecting toward the axis of said can, above the upper end of the can and engageable by the blade in its downward travel to definitely limit such travel, and a ledge on the lower end of the support forming a seat for the can, said ledge projecting toward the can axis, and a seating element for a smaller can of a height materially less than that intended to seat on said ledge, such element being slidable in said support to and from the axis of a can engaged by the support and being predeterminedly upwardly spaced from said ledge, whereby said element when shifted toward the can axis serves to seat said smaller can and when shifted from said axis permits functioning of said ledge to seat a larger can.

2. A can opener as set forth in claim 1, said seating element being a pin disposed transversely to the support and having its ends headed to limit sliding of such pin.

3. A can opener as set forth in claim 2, said support having a rib extending centrally and longitudinally of the support, and deflected to one side of the support, whereby an elongated recess is formed at the opposite side of the support, said recess receiving one of the heads of said pin in a limiting position of sliding of the pin.
